Primary Examiner — Cynthia M. Chin

(57) **CLAIM**

The ornamental design for a multi-functional educational toy grape bead, as show and described.

DESCRIPTION

FIG. 1 shows a side view of the bead showing my new design;

FIG. 2 shows a perspective side view where the bead is slightly tilted to the right side;

FIG. 3 shows a perspective view of the bottom half of the bead, shown separately for ease and clarity of illustration;

FIG. 4 shows a perspective view of the top half of the bead, shown separately for ease and clarity of illustration;

FIG. 5 shows a perspective view of the bottom half of the bead, shown separately for ease and clarity of illustration; and,

FIG. 6 is a cross-sectional view taken from line 6-6 of FIG. 1.

The screw threads and inside of the bead does not form part of the claimed design.

1 Claim, 6 Drawing Sheets(56)
